UNITED STATES PATENT OFFICE.

WILLIAM JOSEPH HOSCEIT, OF CHICAGO, ILLINOIS.

DOOR-LOCK MECHANISM.

1,311,561.

Specification of Letters Patent.

Patented July 29, 1919.

Application filed October 25, 1917. Serial No. 198,441.

To all whom it may concern:

Be it known that I, WILLIAM JOSEPH HOSCEIT, a citizen of the United States, and resident of Chicago, in the county of Cook and State of Illinois, have invented certain new and useful Improvements in Door-Lock Mechanism, of which the following is a specification.

This invention relates to railway cars and 10 more particularly to door lock mechanism therefor.

One of the objects of my invention is to make it necessary to open a given door on railway cars before a second given door can 15 be opened.

Another object is to make it necessary to close a given door of a railway car before a second given door can be closed.

Another object is to interlock a plurality 20 of railway car doors to meet the various requirements for successful commercial use.

These and other objects are accomplished, generally speaking, by providing in a railway car, the combination of a plurality of 25 doors and lock means associated therewith whereby said doors must be actuated in a given sequence.

The invention is illustrated on the accompanying sheets of drawings, in which,

30 Figure 1 is a fragmentary sectional plan view taken in the plane of line 1—1 of Fig. 2 showing the floor in plan and embodying my invention;

35 Fig. 2 is a fragmentary side elevation of a freight car showing the interlock between the side door and drop doors of the car;

Fig. 3 is a fragmentary sectional view of a car taken in the plane of line 3—3 of Fig. 2, showing the drop doors in raised or closed 40 position;

Fig. 4 is a similar sectional view showing the drop doors in lowered or open position;

Fig. 5 is a detail side elevation of the lock actuating mechanism;

45 Fig. 6 is a detail sectional view of the same taken in the plane of line 6—6 of Fig. 5; and

Fig. 7 is a detail view taken in the plane of line 7—7 of Fig. 1, showing means for 50 locking the drop doors in closed position.

The various novel features of my invention will be apparent from the following description and drawings, and will be particularly pointed out in the appended 55 claims.

This invention has particular reference to

that type of railway freight car which has doors in its floor and also at the sides whereby the car not only may be used for carrying various kinds of material which may be dumped by operating the doors, but also a car which is suitable for carrying cattle and the like, in which case, it is necessary that the drop doors be positively locked in their upper or closed position.

By referring to the figures of the drawings, it will be noted that we have shown a freight car 10 having a center sill 11, an intermediate sill 12 and a side sill 13, which support portions of the floor 14. Both sides 70 of the car being the same, only one side will be considered in detail.

Pivotaly connected to the floor 14 or to the intermediate sill 12, or to both, are a plurality of drop doors 15 which are arranged to swing downwardly and inwardly toward the center of the car for the purpose of dumping the contents of the car. These drop doors 15 normally are held in their raised or closed position by four shafts 16, 75 one for each quarter of the car, or in other words, two on each side of the car running lengthwise thereof. As shown in Fig. 3, the drop doors 15 are held in closed position by one of the shafts 16, said shaft occupying a 80 recessed portion 17 formed in a casting or forging 18 extending transversely of the car and also having a central opening 19 in which the shaft 16 may move laterally with 85 respect to the car. This member 18 is provided with an inclined portion 20 down which the shaft 16 rolls when the shaft is being moved toward the center of the car for permitting the drop doors to open. The 90 actuating mechanism for the shaft 16 may 95 be of any suitable type, such for instance, as that shown in my co-pending application Serial No. 190,505, filed September 10, 1917, including sets of chains, each set including two chains 21 and 22, the former having one 100 end secured to the side sill 13 and the other end secured to a sheave 23 mounted on the shaft 16, and the other chain having one end connected to the intermediate sill 12 and its other end connected to another sheave 24 105 also secured to the shaft 16. It is apparent, therefore, that if the shaft is rotated in a clockwise direction, as shown in Figs. 3 and 4, that the shaft will be moved to the right toward the center of the car whereupon the 110 chain 21 will be unwound from its sheave and chain 22 wound upon its sheave.

Each side 25 of the car is provided with a door 26 which, as usual, is mounted for a sliding movement longitudinally with respect to the car. It is with respect to the 5 side doors 26 and the drop doors 15 that we are particularly concerned; that is to say, that in such a combination car we want to make it impossible to open the drop doors before the side doors are opened and also 10 to make it impossible to close the side doors unless the drop doors are closed.

The lock mechanism by means of which such is made possible, includes transversely movable lock members 27 pivotally connected at 28 to retaining members 29 the former being slidable through guide casting 30, (see Figs. 3, 4 and 7) secured to the side sills 13 and also being slidable in a casting 31 secured to the under structure of 20 the car. This member 31 may be in a single casting; or it may be built up in any suitable manner whereby side walls are provided in which there are elongated slots 32 in which the pin 28 connecting the lock member 27 and member 29 may slide and by 25 means of which the movements of the lock member 27 and the retaining member 29 are limited.

As shown in Fig. 3 of the drawing, the 30 member 29 is in a raised position, its notched portion 34 receiving the shaft 16 in such a manner that the shaft is locked against lateral movement. The member 29 in turn is held in its raised position through the 35 coöperation of the lock member 27 and a key 35, which, as shown in Fig. 3, occupies a notch 36 in the lock member 27. In other words, with the parts as shown in Fig. 3, it is impossible for the lock member 27 to 40 move toward the right and therefore impossible for the member 29 to move to the right and downwardly thereby preventing lateral movement of the shaft 16 to the right and preventing opening of the drop doors 15. 45 In order that the drop doors may be opened, it is necessary that the key 35 be operatively disengaged from the notch 36 in the lock member 27. When the key 35 is moved out of the locking position with respect to the 50 lock 27, the shaft 16 may be actuated toward the center of the car whereupon the drop doors 15 may move into an open position where they may rest upon suitable stops 37. It will be noted that a portion of the member 55 29 falls into engagement with, is received by and rests in the inclined channel portion 38 of the member 31 with the projection 39, forming one of the walls of the notch 34, below the path of movement of the 60 shaft 16 whereby the latter may freely move to the right. It will be noted also that the pin 28 occupies the inner end of the slot 32 in the member 31.

By referring to Figs. 1 and 2 of the drawings, it will be noted that the key 35 extends

longitudinally of the car. As shown, the key is in locking position to prevent not only an inward unlocking sliding movement of the lock 27, but also to prevent an inward 70 unlocking sliding movement of another lock 40, which is associated with the second shaft section 16. If the key 35 is shifted to the right from the position shown in Fig. 2, a notch 41, formed near the right hand end of the key 35, will pass into a position to permit the lock 27 to move inwardly and at the same time the left hand end of the key 35 will move out of a notch in lock 40 corresponding to the notch 36 in lock 27 to permit the lock 40 to move inwardly 80 whereupon the parts may change their various positions from that shown in Fig. 3, to the positions shown in Fig. 4; or in other words, the drop doors are permitted to move from a closed position to an open position. 85

The key 35 is actuated by means of a pinion 42 which meshes with a tooth portion 43 of the key 35. The pinion 42 is preferably formed integrally with a member 44 pivotally mounted upon a shaft 45 which is 90 supported by the side sill 13. The member 44 is provided with a notch 46 for the reception of a projection 47 on a dog 48 pivotally mounted at 49 to any suitable support, said dog having an upwardly extending projection 50 which lies directly below the lower edge of the side door 26, so that it is impossible to rotate the member 44 in a clockwise direction to shift the key 35 to an unlocking position unless the door 26 is opened or 100 moved beyond the projection 50.

By means of this locking arrangement it is apparent that with the parts as shown in Figs. 1, 2 and 3, it is impossible to unlock the drop doors 15 until the side doors 26 are 105 moved into an open position. When the side doors 26 are moved into an open position beyond the projection 50, the member 44 may be rotated in a clockwise direction as viewed in Fig. 2 to shift the key 35 to the 110 right to release the shafts 16 whereupon the drop doors may be moved to an open position. When the projection 47 is locked within the notch 46 of the member 44, it is impossible to shift the key 35. However, 115 with the side door moved beyond the projection 50, the projection 47 of the dog 48 may be moved out of the notch 46 whereupon the key 35 may be actuated by a rotation of member 44 for releasing the drop doors 15. 120 It will be noted that after the projection 47 is moved out of the notch 46, and the member 44 is rotated for actuating the key 35, the projection 47 will ride upon the shoulder 51 of the member 44 whereupon the projection 50 will be held up in a position to prevent closing of the side door 26. It is apparent therefore that before the side door can be moved to a closed position, it is necessary first that the drop doors be moved into a 130

closed position and locked before the notch 46 of member 44 will present itself to receive the projection 47 of the dog 48. As soon as the notch 46 is placed in a position to receive the projection 47 the dog 48 will swing 5 downwardly about its pivotal point 49 to carry the projection 50 below the path of movement of the side door whereupon the latter may be moved into a closed position.

10 It is necessary that the drop doors 15 be completely raised to their closed position before they may be locked in such position by the key 35 coöperating with the locks 27 and 40. When the drop doors 15 are 15 moved into their closed position and the key 35 is moved into position shown in Fig. 3 of the drawings and the side door is moved back into its closed position, the drop doors 15 will be prevented from being 20 opened accidentally, or as a matter of fact, by the key 35. When the drop doors 15 are 25 moved into their closed position and the key 35 is moved into position shown in Fig. 3 of the drawings and the side door is moved back into its closed position, the drop doors 15 will be prevented from being opened accidentally, or as a matter of fact, by the key 35. The locking mechanism intermediate the side doors and the drop doors forms an efficient interlock between said parts.

It is apparent that there may be various modifications of the arrangement herein particularly shown and described, and it is 30 my intention to cover all such modifications which do not involve a departure from the spirit and scope of the invention as set forth in the following claims.

35 I claim:

1. In a railway car, the combination of a 40 movably mounted door in the floor of the car, a side door at all times out of engagement with said floor door, and means associated with said doors whereby the side door must be opened before the other door can be opened.

2. In a railway car, the combination of a 45 plurality of movably mounted doors located in different parts of the car and out of engagement with each other, and means associated therewith whereby one of said doors must be opened before another of said doors can be opened.

50 3. In a railway car, the combination of a plurality of movably mounted doors located 55 in different parts of the car and out of engagement with each other, and means associated with said doors whereby one of said doors must be actuated before the other can be actuated.

4. In a railway car, a movably mounted door mounted in the floor of the car, a 60 movably mounted door on one of the walls of the car, said doors at all times being out of engagement with each other, and means associated with said doors whereby it is necessary to actuate the wall door before the floor door can be actuated.

65 5. In a railway car, a movably mounted

door mounted in the floor of the car, a movably mounted door in one of the walls of the car, and means whereby under certain conditions the floor doors must be actuated before the wall door can be actuated.

70

6. In a railway car, the combination of a door movably mounted in the floor of the car, a door movably mounted on the side of the car, and means associated with said doors whereby the side door must be opened 75 before the floor door can be opened and whereby the floor door must be closed before the side door can be closed.

7. In a railway car, the combination of a plurality of car doors located in different 80 parts of the car and out of engagement with each other, and means associated with said doors whereby the same must be actuated in a given sequence.

8. In a railway car, the combination of a 85 plurality of doors located in different parts of the car and out of engagement with each other, and an interlock between said doors.

9. In a railway car, the combination of a 90 door movably mounted in the floor of the car, a door movably mounted on a side of the car, and separate interlock mechanism between said doors.

10. In a railway car, the combination of a 95 movably mounted door in one portion of the car, a second movably mounted door in another portion of the car, a lock member which takes a given position when one of said doors is closed, and a key member having a locking action on said lock member 100 when the other door is closed.

11. In a railway car, the combination of a 105 movably mounted door in the floor of the car, a side door for the car, and separate interlock mechanism between said doors which comprise relatively movable members.

12. In a railway car, the combination of a 110 movably mounted door in the floor of the car, a side door for the car, an interlock between said doors including a transversely movable member associated with one of said doors, and a longitudinally movable coöperating member associated with another of said doors.

13. In a railway car, the combination of a 115 door in the floor of the car, a side door for the car, and locking means for said doors interposed between the same and including a notched member and a movably mounted member coöperating with said notched member.

14. In a railway car, the combination of a 120 door movably mounted in the floor of the car, a side door for the car, a member normally holding the floor door in its closed 125 position, a member for retaining said holding member in such position, a lock member connected to said retaining member, and locking means associated with the other door and coöperating with said lock member.

130

15. In a railway car, the combination of a movably mounted door in the floor of the car, a side door for the car, a member normally holding the floor door in closed position, a notched member for normally retaining the holding member in a given position, a lock member for holding said retaining member in a given position, and a movable key associated with the other door for locking the lock member in a given position.
16. In a railway car, the combination of a movably mounted door in the floor of the car, a side door for the car, a member normally holding the floor door in closed position, a notched member for normally retaining the holding member in a given position, a lock member for holding said retaining member in a given position, a movable key associated with the other door for locking the lock member in a given position, and means for actuating said key member.
17. In a railway car, the combination of a movably mounted door in the floor of the car, a side door for the car, a member normally holding the floor door in closed position, a notched member for normally retaining the holding member in a given position, a lock member for holding said retaining member in a given position, a movable key associated with the other door for locking the lock member in a given position, and means controlled by the position of the side door for actuating said key member.
18. In a railway car, the combination of a movably mounted door in the floor of the car, a side door for the car, a member normally holding the floor door in closed position, a notched member for normally retaining the holding member in a given position, a lock member for holding said retaining member in a given position, a movable key associated with the other door for locking the lock member in a given position, and guide means for said retaining member and lock member.
19. In a railway car, a plurality of movably mounted doors and locking mechanism between said doors including a member normally holding one of said doors in a given position, a member for locking the holding member in said position, and a guide member in which said holding member and lock member are movably and guidably mounted.
20. In a railway car, the combination of a plurality of movable doors, and locking mechanism between said doors including a member for normally holding one of said doors in a given position, a lock member pivotally connected to said holding member, and a guide member in which the holding member and locking member are movably mounted and whereby the holding member may assume an elevated or lowered position in accordance with locking conditions.
21. In a railway car, the combination of a plurality of movably mounted doors, and locking means extending therebetween and including a lock member associated with one of said doors, a key, means for actuating said key, and a member controlled by the other door for controlling said actuating means.
22. In a railway car, a plurality of movably mounted doors, and locking mechanism therebetween including a movably mounted locking member, means for actuating said member, and a pivotally mounted dog associated with said means for locking the latter when one of said doors is in a given position.
23. In a railway car, the combination of a plurality of movably mounted doors, and means extending between said doors whereby it is necessary that one of said doors be opened before the other one can be opened, and means under certain conditions extending in the path of movement of one of said doors whereby one of said doors must be closed before the other of said doors can be closed.
- Signed at city of Chicago, State of Illinois, this 25th day of September, A. D. 1917.
- WILLIAM JOSEPH HOSCEIT.
